INCUBATOR

John F. MacKay, Lancaster, Pa.

Application November 3, 1928, Serial No. 316,922

15 Claims. (Cl. 119—42)

This invention relates to incubators, and more particularly to hatching structures of the vertical or cabinet type with incubating chambers capable of accommodating a multiplicity of egg trays arranged in superposed relation. In consequence of the height of incubators of the specific kind referred to, the problem of effectively controlling temperature conditions and air circulation is considerably more involved than is the case with incubators of the horizontal or deck variety.

It is with the solution of the above indicated drawbacks in cabinet incubators that my present invention is directly concerned, my aim being to insure maintenance, automatically, of the proper temperatures throughout the incubating period in spite of the counter effects attending gradual development of natural or animal heat in the eggs as the process of incubation advances, and at the same time to provide for replacement of foul air within the incubating chambers by fresh air without appreciably disturbing the temperature.

In the drawings, Figure I shows a front elevation of an incubator structure conveniently embodying my invention.

Fig. II is a plan view of the organization.

Figs. III and IV are plan sectional views in different horizontal planes, taken as respectively indicated by the arrows III—III and IV—IV in Figs. I and V.

Fig. V is a transverse sectional view of the incubator, taken as indicated by the arrows V—V in Figs. I, II, III and IV.

Fig. VI is a perspective illustration of the means by which the proportioning of co-mingled fresh and pre-heated air is controlled incidental to entry into the incubation chambers; and,

Fig. VII is a detail view showing the construction of a flow-regulating valve associated with the fluid medium heating system of the incubator.

As herein depicted, my improved incubator embodies a casing which affords a series of separate incubating chambers 10 each accommodating, in the present instance, four symmetrically arranged groups of egg trays 11 disposed in superimposed relation. These egg trays 11 are slidably supported upon guide rails 12, extending transversely of the chambers 10, and are accessible from opposite sides of the structure through double doors 15. The chambers 10 are heated by pipe coils 16 extending around their bottoms, and vented through outlets 17 in their tops, there being preferably four such outlets, one centrally above each of the stacks of trays 11, see Figs. I and

II. Venting through the outlets 17 is governed by dampers 18 subject to automatic control, individually, by suitable temperature responsive thermostat devices 19 located within the incubating chambers 10.

For the purpose of admitting fresh air into the incubating chambers 10 to supplant the foul air vented through the outlets 17, I provide said chambers with openings 20 through their floors, said openings being centrally located, as shown in Fig. IV. The fresh air so admitted to each chamber 10 is agitated by a rotary fan 21 lying substantially in the same plane as the heating coil 16. Each such fan 21 is mounted on a shaft 22 which extends down through the midst of the respective groups of the trays 11 in the incubating chambers 10, said shaft having support at its lower end in a bridge bearing 23 over the opening 20, and at the top in a bearing 24 on the roof of the incubator. Any suitable means may be provided to slowly rotate the fan shafts 22, for example, separate electric motors 25 with pulley belt connections 26, see Figs. I, II and V.

At the base the structure is hollow with provision of a vertically shallow interval 27, (Figs. I and V) which, through longitudinal and transverse partitions 28, 29, is subdivided into a plurality of compartments 30, in this instance two beneath each of the incubating chambers 10, and a comparatively narrow separating channel 31 extending medially of the length of the incubator. Outside air is admitted into the compartments 30 through apertures 32 in the incubator bottom 33, which, as shown in Figs. I and V is elevated from the floor. The air so admitted is heated by contact with the longitudinal pipes 34a of coils or radiators 34, where-

of there are two, one serving each pair of longitudinally adjacent compartments 30. As shown, the pipes 34a of the radiators 34, are joined by transverse manifold headers 34b, 34c which are preferably located exteriorly of the incubator for convenience and ease of assembly. Flow of warmed fresh air from the heating compartments 30 into the incubating chambers 10 is controlled by hollow valve means 35, the latter being independently slideable along the channel 31, between the incubator bottom 33 and the floor of the incubating chambers 10 across the inlet ports 20 aforementioned. Each such valve means 35 is fashioned to rectangular or box-like formation from sheet metal, and provided at opposite sides, near one end, with transversely aligned cut outs 36 (Fig. VI) capable of registry, to various extents, with lateral out flow 410

openings 37 of the compartments 30 through the lengthwise partitions 28, see Fig. III, said openings being in line with the inlet ports 20 of the chamber 10. At the opposite end, the 5 hollow valve 35 has an orifice 38 capable of registry, likewise to various extents, with a fresh air port 39 through the bottom 33 of the incubator. This port 39 is co-axial with the port 20 but is disposed in a plane at right angles below 10 and between the flow openings 37 from the heating compartments 30. The slide valves 35 are operable by means of levers 40 with fulcrum support at 41, said levers being provided at their free ends with handles 42 which are accessible 15 from one side of the incubator. With this arrangement it will be obvious that fresh air and preheated air can be concurrently admitted into the incubating chambers 10 separately or in varying proportions, as required or desired, with 20 assurance of co-mingling of the two streams as a consequence of having to traverse the hollows of the valves 35 en route to said chambers.

The heating system for the incubator further 25 comprises a heater 45 (Figs. I, II and III) located at a level somewhat below that of the floor plane. A flow main 46 reaches up from the heater and over the top of the incubator, and has branches 47 which lead downward through the respective incubating chambers 10 30 to the heating coils 16 in them. To individually control flow of the heating medium through the pipe branches 47 automatically, in accordance with temperature conditions existing in the chambers 10, I interpose valves 48 in the pipe branches 47, one such valve 48 being detailed 35 in Fig. VII. As shown, the valve has a tapered closure member 49 to co-act with a seat 50 within the valve body, and an actuating stem 51 reaching upward through an extension neck 52 40 via which air is vented through lateral ports 52a. In each instance, the valve 48 is controlled by a thermostatic temperature responsive device 53 in the corresponding incubating chamber 10, said device having a lever 54 connecting with 45 the actuating stem 51 of the valve 48. Thus with increase of temperature in the incubating chamber 10 and expansion of the thermostat temperature responsive device 53, the valve 48 is automatically moved to closed position to intercept 50 further flow of the heating medium through the coil 16 until the desired normal temperature conditions are restored, whereupon a converse action takes place to re-establish flow as required. From Figs. I, III and V it will be observed that 55 return flow from the coils 16 within the chambers 10 is by way of a pipe 55 which extends through the hollow base 27 of the incubator. In order that the radiators 34 within the compartments 30 may function entirely independently 60 of the coils 16, separate connections are made with the heater 45 as follows: a flow pipe 56 extends from said heater and branches out in opposite directions as at 57 for connection into the headers 34b of the radiators 34. Similarly, 65 return pipes 58 extend from the headers 34c through the heating compartments 30 and, at their opposite ends join a transverse branch 59 which in turn connects with a pipe 60 that leads direct into the heater 45. Hand valves 61 and 70 62 are interposed in the pipes 46 and 56, respectively to enable individual general control of the two separate circuits of the heating system.

From the foregoing, it will be seen that my improved incubator represents a multi-chamber 75 structure wherein cold and preheated fresh air

may be admitted, in regulatable relative quantities, into the chambers 10 independently to replace foul air vented under automatic thermostatic control. By assurance of co-mingling of the cold and preheated fresh air streams in the hollows of the slide valves 35 with consequent moderation of the temperature in the mixture, chilling of the eggs is prevented notwithstanding rapidity of air circulation. This is of prime importance in connection with upright or cabinet incubators where rapid upward flow of the air is materially promoted by virtue of their height. My incubator is moreover unique in that the means for heating the chambers 10 and for preheating influx air, although supplied from the same heater 45, are entirely independent of one another and therefore immune against counter influence. Furthermore, as a consequence of allocation in the hollow base 27 of the structure, the air preheating coils 34 operate to offset chilling influences from beneath, thereby facilitating maintenance of a uniform temperature in the incubator. During the operation of the incubator, the rotating fans 21 gently agitate the air within the chambers 10, thereby 100 distributing the same thoroughly to penetrate the superimposed trays 11 of the several stacks in each chamber and to circulate freely about the eggs on said trays. The fans 21 also counteract the direct radiating effect of the coils 16 105 upon the eggs in the lowermost trays 11 of the stacks. An absolutely uniform temperature is thus maintained within the incubating chambers 10 at all times with avoidance of dead air pockets at the corners. 110

I claim:

1. In an incubator, an incubating chamber with a hollow bottom having an air inlet port and a superjacent concentric outlet therefrom; and valve means controlling flow of fresh cold air and preheated fresh air through the outlet, said valve means having a hollow wherein the two air streams are co-mingled previous to induction into the incubating chamber. 115
2. In an incubator, an incubating chamber with a hollow bottom having an air inlet port and a superjacent concentric outlet therefrom; and valve means controlling flow of cold fresh air and preheated fresh air through the outlet in varying proportions, said valve means being 120 of box-like formation to afford a hollow wherein the two air streams are caused to co-mingle previous to induction into the incubating chamber. 125
3. In an incubator, an incubating chamber with a hollow bottom having an air inlet port and a superjacent concentric outlet therefrom, said hollow bottom providing a separate heating compartment; and slidable box-like valve means 130 controlling admission of cold fresh air from the exterior and of preheated fresh air from the heating compartment with assurance of co-mingling previous to induction into the incubating chamber. 135
4. In an incubator, an incubating chamber with an air admission orifice in the floor thereof; a shallow heating compartment separate from and underlying said chamber with a fresh air inlet in its bottom; and slidable box-like means 140 to control admission of fresh cold air and preheated fresh air at the same time through the admission orifice with assurance of co-mingling previous to induction into the incubating chamber. 145
5. In an incubator, an incubating chamber 150

- with a hollow bottom providing a number of separate heating compartments having air inlet apertures and outlet openings; and valve means cooperative with spaced concentric orifices in the hollow bottom controlling admission, concurrently, of cold fresh air from the exterior and of preheated fresh air from the several heating compartments into the incubating chamber.
6. In an incubator, an incubating chamber with an air admission orifice in its bottom; separate parallel heating compartments underlying said chamber with an intervening channel; and hollow valve means slidable in the channel for controlling, concurrently, admission of fresh cold air from the exterior by way of an opening in the channel base, concentrically below the admission orifice, and of preheated fresh air from the several heating compartments with assurance of co-mingling previous to induction through the air admission orifice aforesaid into the incubating chamber.
7. In an incubator, an incubating chamber with a pipe coil therein around its bottom for heating it and thermostatically-controlled outlets at the top for venting it; a compartment separate from the incubating chamber also having a heating coil therein; a heater common to the several coils and with connections insuring independent circulation of heating medium in each; and a box-like valve for controlling admission of preheated fresh air from the compartment into the incubating chamber to replace foul air vented from said chamber.
8. In an incubator, an incubating chamber with a coil therein for heating it and means for venting it; a compartment separate from the incubating chamber also having a heating coil therein; a heater with individual connections to the several coils to insure independent circulation of heating medium in each and a return pipe for the chamber heating coil extending through the compartment aforesaid; and means for controlling admission of preheated fresh air from the compartment into the incubating chamber to replace foul air vented from said chamber.
9. In an incubator, an incubating chamber to accommodate a multiplicity of symmetrically-arranged groups of egg trays in superimposed relation, said chamber having heating means in its bottom and a vent in its top, an underlying compartment separate from the incubating chamber with means defining a medially located longitudinal separating channel and also having heating means therein; and hollow box-like means with opposing cut outs for controlling admission of preheated fresh air from the compartment into the incubating chamber to replace foul air vented from said chamber.
10. In an incubator, an incubating chamber with a coil extending around its bottom for heating it and means for venting it at the top; a compartment separate from and below the incubating chamber also having a heating coil therein; a heater with individual connections to the several coils to insure independent circulation of heating medium in each and a return pipe for the chamber heating coil extending through the compartment aforesaid; means for controlling admission of preheated fresh air from the compartment into the incubating chamber to replace foul air vented from said chamber.
11. In an incubator, an incubating chamber to accommodate a multiplicity of egg trays stacked in spaced superposed relation, said chamber having an air inlet port in its bottom and a horizontal fan beneath the lowermost tray of the stack rotating concentrically over said port; a separate heating compartment underlying the incubating chamber; and means controlling admission of preheated fresh air from the compartment into the incubating chamber through the inlet port aforesaid.
12. In an incubator, an incubating chamber having a hollow bottom partitioned to define a comparatively narrow channel between air-preheating compartments, said channel having a fresh air inlet port and an outlet port as well as opposed apertures communicating into the compartments aforesaid, and a hollow member slidably-fitting the channel with manipulator means, said member having openings adapted to control concurrent admission of cold air and preheated fresh air separately or in varying proportions with assurance of co-mingling previous to induction into the incubating chamber as a consequence of passage through the hollow member aforesaid.
13. In an incubator including an incubating chamber with means therein around its bottom for heating it and means for venting it at the top, the combination of a separate source of preheated fresh air below said chamber having inlet and outlet apertures, and a box-like valve having lateral openings for variable registration with said outlet apertures from the separate source of preheated fresh air for controlling admission of preheated fresh air into the incubating chamber to replace foul air vented from said chamber.
14. In an incubator including an incubating chamber with a coil therein at its bottom for heating it, and means for venting it at the top, the combination of sub-compartments separate from and below the incubating chamber with fresh air inlet and outlet openings and also having associated heating means therein, and a box-like valve having lateral cutouts adapted for variable registry with the outlet openings aforesaid for controlling admission of preheated fresh air from the sub-compartments into the incubating chamber to replace foul air vented from the latter.
15. In an incubator, an incubating chamber with a main air admission orifice in its bottom; a number of heating compartments, each having a plurality of air inlets and an air outlet, separate from and underlying said chamber with formation of a hollow bottom therefor including a dividing channel; and means controlling admission of cold fresh air from the exterior, by way of a supplemental port in the base of the hollow bottom, concurrently with the preheated fresh air from the several heating compartments, entering the incubating chamber through the main air admission orifice aforesaid in varying proportions from the dividing channel aforesaid.

JOHN F. MACKAY.
